UNITED STATES PATENT OFFICE.

CLARK T. HENDERSON, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLER.

1,339,456.

Specification of Letters Patent. Patented May 11, 1920.

Application filed June 5, 1915. Serial No. 32,424.

To all whom it may concern:

Be it known that I, CLARK T. HENDERSON, a citizen of the United States, residing at Milwaukee, in the county of Milwaukee and State of Wisconsin, have invented new and useful Improvements in Circuit-Controllers, of which the following is a full, clear, concise, and exact description, reference being had to the accompanying drawing, forming a part of this specification.

This invention relates to improvements in circuit controllers.

More particularly the invention relates to circuit breakers, especially those of the overload type and has among its objects to provide a simple and effective controller of this character which will be insured against telegraphing.

A further object is to provide a simple and effective protective controller of the aforesaid character wherein two single pole electromagnetic switches are employed as a double pole switch.

Other objects and advantages will hereinafter appear.

The accompanying drawing diagrammatically illustrates one embodiment of the invention and the same will now be described, it being understood that the controller illustrated is only one of the possible embodiments of the invention.

The controller illustrated includes two electromagnetic switches 1 and 2 to complete circuit between supply lines L and L' and translating lines 1 and 1', said switches constituting the equivalent of a double pole switch. Also the controller includes two overload switches 3 and 4 for tripping the line switches 1 and 2 and a push button control switch 5 together with auxiliary contacts associated with the switch 2 to effect setting of the line switches.

The overload switches 3 and 4 have their operating windings connected in opposite sides of the circuit and both switches are included in series with the operating winding of each line switch. Thus it will be apparent that response of either overload switch will interrupt the circuit of both line switches, thereby effecting interruption of both sides of the controlled circuit.

The push button control switch 5 is provided with a pair of down contacts 6 and a pair of up contacts 7. Bridging of the down contacts completes an energizing circuit for

the line switch 2 while bridging of the up contacts establishes a maintaining circuit for the switch 2 and an energizing circuit for the switch 1, said last two mentioned circuits being also dependent upon response of switch 2 to bridge its auxiliary contacts 8, 9 and 10.

More specifically describing the circuit connections, when the switch 5 is depressed it completes circuit from line L by conductors 11 and 12, through the winding of switch 2, by conductor 13, through the overload switch 3, by conductor 14, through the overload switch 4, by conductor 15 to line L'. Thus switch 2 will at once respond to complete one side of the controlled circuit and to bridge its auxiliary contacts 8, 9 and 10. This establishes a maintaining circuit for the switch 2 from line L, by conductors 11 and 16, through auxiliary contacts 8 and 10, by conductor 17, to and through the winding of switch 2, as already traced. Switch 1, however, will not respond and in consequence the controlled circuit will not be completed until the push button switch 5 is released. When switch 5 is released it completes circuit from line L, by conductors 11 and 16, through auxiliary contacts 8 and 9 of switch 2, through its up contacts 7, by conductor 19, through the winding of switch 1, to conductor 18 and thence through both overload switches to line L', as already traced. Switch 1 thereupon responds to complete the controlled circuit subject to subsequent interruption by response of either overload switch. As before stated upon response of either overload switch both line switches are deenergized.

It will thus be observed that energization of switch 1 is dependent upon prior and continued energization of switch 2 as well as release of the control switch 5 while continued energization of switch 2 following the release of switch 5 is dependent upon its own auxiliary contacts. Obviously therefore, after the switches 1 and 2 have once been tripped they can only be reset by repeating the operation of the control switch as described above, thereby positively insuring against automatic resetting or telegraphing thereof.

What I claim as new and desire to secure by Letters Patent is:—

1. In a circuit controller, in combina-

- tion, a plurality of electro-responsive line switches, means to deenergize said switches upon the occurrence of abnormal electrical conditions in the controlled circuit, and circuit connections for said switches necessitating energization of one prior to energization of another, to insure against reestablishment of the controlled circuit until normal conditions are restored.
10. 2. In a circuit controller, in combination, a plurality of electro-responsive line switches, means to deenergize the same upon the occurrence of abnormal electrical conditions in the controlled circuit, a common control device for the operating windings of said switches and circuit connections necessitating response of one of said switches prior to another and different settings of said control device for completion of the energizing circuits of said switches, to insure against telegraphing of the latter after deenergization by said means and to insure against reestablishment of the controlled circuit until normal conditions are restored.
15. 3. In combination, a plurality of electro-responsive line switches, a controller therefore, automatic tripping means for said switches and circuit connections insuring against telegraphing of any one of said switches after tripping thereof irrespective of the retention of said controller in any position thereof.
20. 4. In combination, a plurality of electro-responsive line switches, a controller therefore, automatic tripping means for said switches and circuit connections necessitating a number of progressive operations of said controller to effect energization of said switches after tripping of either.
25. 5. In combination, a plurality of electro-responsive line switches, a controller therefore, automatic tripping means for said switches and circuit connections necessitating energization of said switch progressively by progressive movements of said controller to different circuit controlling positions.
30. 6. In combination, a plurality of electro-
- responsive line switches, a controller therefore, automatic tripping means for said switches and circuit connections necessitating energization of said switches progressively and rendering the response of the first switch dependent upon a predetermined operation of said controller while rendering the response of the next switch dependent upon a subsequent operation of the controller.
35. 7. In combination, a plurality of electro-responsive line switches, a controller therefore, automatic tripping means for said switches and circuit connections necessitating energization of said switches progressively and rendering the response of the first switch dependent upon a predetermined operation of said controller while rendering the response of the next switch dependent upon subsequent operation of the controller and prior response of the first switch.
40. 8. In combination, a plurality of electro-responsive switches, one controlling the energizing circuit of the other and a maintaining circuit for itself, a controller for said switches, circuit connections rendering the energization of one of said switches dependent upon predetermined positioning of said controller and the energization of the other of said switches dependent upon movement of said controller to another position and automatic tripping means for one of said switches.
45. 9. In combination, a plurality of electro-responsive line switches, one controlling the energizing circuit of the other and a maintaining circuit for itself, a controller for said switches, circuit connections rendering the energization of one of said switches dependent upon predetermined positioning of said controller and the energization of the other of said switches upon movement of said controller to another position and automatic tripping means common to both of said switches.

In witness whereof, I have hereunto subscribed my name.

CLARK T. HENDERSON.
